(Continued)*Primary Examiner* — Mitchell I. Siegel(74) *Attorney, Agent, or Firm* — Michael A. Catania(57) **CLAIM**

The ornamental design for a golf club head, as shown and described.

DESCRIPTION

FIG. 1 is a rear elevation view of a golf club head;
FIG. 2 is a front elevation view thereof;
FIG. 3 is a top plan view thereof;
FIG. 4 is a bottom plan view thereof;
FIG. 5 is a toe-side elevation view thereof;
FIG. 6 is a heel-side elevation view thereof;
FIG. 7 is a top perspective view thereof; and,
FIG. 8 is a top perspective view of the golf club head connected to a shaft in broken lines.
The broken lines shown in the drawings form no part of the claimed design.
